UNITED STATES PATENT OFFICE.

CARL FRIEDRICH HERMANN WEISSE, OF OTTENSEN, PRUSSIA, ASSIGNOR TO
JOHANN HEINRICH EHLERS, OF BAHRENFELD, GERMANY.

CAR-COUPING.

SPECIFICATION forming part of Letters Patent No. 369,269, dated August 30, 1887.

Application filed April 14, 1887. Serial No. 234,861. (No model.) Patented in Germany June 30, 1885, No. 35,806.

To all whom it may concern:

Be it known that I, CARL FRIEDRICH HERMANN WEISSE, a subject of the German Emperor, and a resident of Ottensen, in the Kingdom of Prussia and German Empire, have invented certain new and useful Improvements in Car-Couplings, of which the following is a specification.

This invention relates to railway-car couplings which are actuated from the side of the car; and the objects of my improvements are to facilitate the coupling and uncoupling of cars and to provide a very secure connection of the same. I attain these objects by the mechanism shown in the accompanying drawings, in which—

Figure 1 is a top view of the ends of two cars coupled together and both provided with my improved coupling device. Fig. 2 is the front view of my improved coupling device, and Fig. 3 the side elevation thereof. Fig. 4 illustrates the manner of attaching the coupling-links of the one car to the hooks of the other.

Similar letters refer to similar parts throughout the several views.

A is the coupling-hook, preferably provided with three arms, $a' a'' a'''$, of which the middle one, a' , is a little shorter than the two outside ones, $a'' a'''$, in order to maintain a rigid connection also when the cars are running on curves. When going straight on, the middle hook, a' , has to stand the strain of the train, while the outside ones serve as safety-hooks.

Pivoted to the hook A by means of the bolt b are two arms, b', to the free ends of which is pivoted, by means of the bolt b'', the coupling-link B, provided with the actual coupling-loop and corresponding with the safety-hooks a' and a'' , with two auxiliary loops. Triangular projections b' are attached to or formed underneath the outside arms of the link B.

The rod a^3 , by which the hook A is connected with the car-body, is provided with shoulders $a^4 a^5$, which bear against coiled springs $a^6 a^7$. Thus the strain on the hook A will be elastically communicated to the car-body, as the springs lie at the cross-bars $d d'$, respectively, of the car. The threaded part a^8 of the rod a^3 serves to adjust the hook A in

proper position and in proper tension toward the other car, as a nut placed between two cross-bars, $d d'$, and rotated by means of suitable chains, $c' c''$, and wheels $c^3 c^4$, causes the longitudinal motion of the rod a^3 , for the above-described purpose. The chain-wheels $c^3 c^4$, being arranged at both sides of the car and connected with hand-wheels $c^5 c^6$, allow to adjust the position of the rod a^3 from the longitudinal sides of the car.

To bring the link B of the one car over the hook A of the adjacent car, there are two arms, E, attached at both sides of the link B to a shaft, e, resting in bearings e^4 on the front side of the car. The free ends of the arms E are connected by a bolt, e', whereon the rollers e^2 are pivoted. When the shaft e is turned suitably by means of one of the handles e^3 , the arms E are raised, thus placing the rollers e^2 under the link B, which is thereby lifted.

In the hanging-down position the front side, b^6 , of the triangle b^4 rests on the roller e^2 , as may be seen in Fig. 3, on the right-hand car. Thus the raising of the lifter-arms E lifts at first the link B, which then swings around the bolt b^2 , while the arms b' remain still in their vertical position; but as the pivot of the arm E is in a lower position than the pivot of the arms b' and behind the same the link B is successively raised until the summit of the triangle b^4 passes over the roller e^2 . Then the link B is pushed forward as the rear incline, b^6 , of the triangle b^4 rolls down on the roller e^2 , thus bringing the link B in proper position over the hook A, into which the link engages when the arm E is left free. To facilitate the motion of the arms E a counter-weight, e^5, is attached by means of the arm e^6 to the shaft e.

As a particular advantage of my improvements, it will be understood that my coupling device can also be applied to old cars without altering the at present employed coupling-hooks, and that a car provided with my improved coupling device can easily be coupled with any car having the ordinary coupling device, as well as with such cars already provided with my invention.

Having now particularly described and ascertained the nature of my said invention and

in what manner the same is to be performed, I declare that what I claim is—

1. In railway-car couplings, the combination of the hook A with the link B, provided with triangles b^4 , arms b' , shaft e , and arms E, substantially as and for the purpose specified.
2. In railway-car couplings, the combination of the hook A and rod a^3 , provided with the threaded part a^4 , with the nut c , chains to $c' c^2$, chain-wheels $c^3 c^4$, and hand-wheels $c^5 c^6$, substantially as and for the purpose specified.

In testimony that I claim the foregoing as my invention I have signed my name, in presence of two witnesses, this 28th day of February, 1887.

CARL FRIEDRICH HERMANN WEISSE.
